GOBLET

George Barradas, Stamford, Conn., assignor to Consolidated Molded Products Corporation, Scranton, Pa., a corporation of Delaware

Application August 2, 1955, Serial No. 37,279

Term of patent 14 years

(Cl. D36—8)

FIG.1.

FIG.2.

FIG.3.

FIG.4.

Fig. 1 is an elevational view of a goblet showing my new design with the stem of the goblet in extended position;

Fig. 2 is an elevational view of the goblet with the stem in retracted position;

Fig. 3 is a top plan view thereof; and

Fig. 4 is a view in section taken on line 4—4 of Fig. 1 showing the base of the goblet.

I claim:

The ornamental design for a goblet, as shown.
